(57) **CLAIM**

The ornamental design for a defibrillator paddle, as shown and described.

DESCRIPTION

FIG. 1 is a top perspective view of the defibrillator paddle having a separable top portion and bottom portion;

FIG. 2 is a bottom perspective view of the defibrillator paddle of FIG. 1;

FIG. 3 is a top view of the defibrillator paddle of FIG. 1; FIG. 4 is a bottom view of the defibrillator paddle of FIG. 1;

FIG. 5 is a front elevational view of the defibrillator paddle of FIG. 1;

FIG. 6 is a rear elevational view of the defibrillator paddle of FIG. 1;

FIG. 7 is a side elevational view of the defibrillator paddle of FIG. 1;

FIG. 8 is a side elevational view of the defibrillator paddle of FIG. 1 taken from the opposite side of FIG. 7;

FIG. 9 is a top perspective view of the top portion of the defibrillator paddle as separated from the bottom portion; FIG. 10 is a top view of the top portion of the defibrillator paddle of FIG. 9;

FIG. 11 is a bottom view of the top portion of the defibrillator paddle of FIG. 9;

FIG. 12 is a front elevational view of the top portion of the defibrillator paddle of FIG. 9;

FIG. 13 is a rear elevational view of the top portion of the defibrillator paddle of FIG. 9;

FIG. 14 is a side elevational view of the top portion of the defibrillator paddle of FIG. 9;

FIG. 15 is a side elevational view of the top portion of the defibrillator paddle of FIG. 9 taken from the opposite side of FIG. 14;

FIG. 16 is a top perspective view of the bottom portion of the defibrillator paddle as separated from the top portion; FIG. 17 is a top view of the bottom portion of the defibrillator paddle of FIG. 16;

FIG. 18 is a bottom view of the bottom portion of the defibrillator paddle of FIG. 16;

FIG. 19 is a front elevational view of the bottom portion of the defibrillator paddle of FIG. 16;

FIG. 20 is a rear elevational view of the bottom portion of the defibrillator paddle of FIG. 16;

FIG. 21 is a side elevational view of the bottom portion of the defibrillator paddle of FIG. 16; and,

FIG. 22 is a side elevational view of the bottom portion of the defibrillator paddle of FIG. 16 taken from the opposite side of FIG. 21.
